CLAIM

The ornamental design for an herb and spice dispenser or similar article, as shown and described.

DESCRIPTION

FIG. 1 is a top, front, left side perspective view of a herb and spice dispenser or similar article showing our new design; and

FIG. 2 is a front elevational view thereof.
